FISH LURE

Joseph D. Bates, Jr., Hampden County, Mass., assignor to Illinois Tool Works, Chicago, Ill., a corporation of Illinois

Filed Aug. 10, 1959, Ser. No. 57,129

Term of patent 14 years

(Cl. D31—4)

Fig. 2

Fig. 1

Fig. 3

Fig. 1 is a front perspective view taken from the left side of a fish lure embodying my new design with the broken-line representation of fishing hooks being shown for illustrative purposes only and the right side being substantially like the left side shown;

Fig. 2 is a front elevational view thereof;

Fig. 3 is a rear elevational view thereof;

Fig. 4 is a top plan view thereof; and

Fig. 5 is a fragmentary left side elevational view showing the front thereof.

I claim:

The ornamental design for a fish lure, as shown and described.
